UNITED STATES PATENT OFFICE.

GEORGE W. EDWARDS, OF DUBLIN, GEORGIA.

STALK CUTTER.

Application filed April 25, 1928. Serial No. 272,827.

This invention relates to improvements in stalk-cutters.

The principal object of the invention is to provide a stalk-cutter of the type known as a 5 "riding" cutter with improved blade-supporting wheels which efficiently perform the function of the usual running wheels which, in this type of cutter, have been eliminated.

Another object of the invention is to provide a stalk-cutter with blade-supporting wheels having felloes whereby these wheels act to support the entire machine as well as the cutter-blades.

A further object is to provide a riding 15 stalk-cutter with blade-supporting wheels upon which the blades are so mounted that a clean cut is insured and at the same time the blades are practically self-sharpening.

Still another object of the invention is to 20 provide a stalk-cutter with an improved non-clogging drum or roller of simple and durable construction which adds materially to the efficiency of the cutter and prevents clogging.

25 Other objects and advantages will in part be obvious and in part more fully brought out as the description of the invention proceeds.

In the accompanying drawings, I have illustrated an embodiment of my invention; but it is to be understood that the drawings are illustrative, merely, and are not to be construed as limiting the invention to the details of construction therein shown. It 30 will be obvious to those skilled in the art that modification may be made without sacrificing any of the advantages of my invention or departing from the salient features thereof.

In these drawings:

40 Fig. 1 is a side elevation of a stalk-cutter of my invention;

Fig. 2 is a rear view thereof;

Fig. 3 is a sectional view, taken on the line 3-3 of Fig. 2; and

45 Fig. 4 is a perspective view of one of my improved blade-supporting wheels.

Referring now to the drawings, the reference numeral 1 indicates, generally, a supporting frame which may be of any well-known construction. Suitably secured to the sides of the frame 1 are the depending brackets 2 which support bearing blocks 3 in which an axle or shaft 4 is journaled.

50 Mounted upon the axle 4, and keyed thereto by any convenient means, are the blade-supporting wheels 5. These wheels are pref-

erably made of cast iron and have a hub 6, a body-portion 7, and a felloe 8, all integrally united. The outside of the body-portion may be dished out or slightly concave, if desired. The felloe 8 is provided with a plurality of equally-spaced integral blade-supporting elements or projections 9—preferably seven in number, as illustrated in the drawings. Each projection is apertured as 65 at 10 for the reception of a bolt 11 by means of which a cutter-blade 12 is secured to the projection. The blade-supporting face of the projections is located at such an angle to the felloe that a line drawn therefrom towards 70 the center of the wheel will not pass through the center. By this angular disposition of the blades, they are thrown perpendicularly to the ground when the wheels rotate, thus insuring a positive cut and, at the same time, 75 the blades are made practically self-sharpening.

Each of the wheels 5 is provided on its inner face with a groove 13 of suitable depth to receive and securely retain the ends of a 80 hollow metallic roller or drum 14 which surrounds the axle 4. The drum 14 is preferably made of heavy sheet metal and is formed by folding into what may be called "star-shape", as clearly shown in Fig. 3. It will, 85 of course, be understood that the shape of the groove 13 is the same as that of the drum, as shown in Fig. 4. The points, or edges, 15 of the drum are located in alinement with the cutter-blades 12 and form, practically, an 90 extension thereof for a desired distance, thus preventing anything becoming wedged between the blades and the drum.

From the points inwardly, the walls of the drum diverge and form a plurality of substantially rectangular pockets 16. These pockets will effectually prevent anything from clogging the cutter, since the cut stalks and dirt cannot become lodged therein but will be discharged therefrom upon rotation 95 of the drum.

By bending sheet metal to form the drum 14 as above described, great strength and rigidity is imparted thereto and the defects and disadvantages of the wooden rollers now 100 in use are overcome.

Suitably mounted upon the frame of the cutter is a spring stem 17 which supports a seat 18 for the driver.

110 It will now be seen that I have provided a practical and efficient stalk-cutter embodying all of the advantages above set forth.

By reason of the shape of the blade-supporting wheels and the fact that they are provided with felloes, side-sway of the cutter is effectually prevented, even though one wheel 5 may be traveling on hard ground and the other on soft ground. Also, where the ground is soft, the felloes prevent the wheels and cutter-blades from sinking too deeply. Thus, in the "riding" type of cutter where the 10 usual running wheels have been eliminated, the blade-supporting felloe wheels of my invention perform all the functions of the discarded wheels without sacrificing any of their 15 advantages.

15. What I claim is:

1. A stalk-cutter including a frame, an axle journaled therein, a pair of blade-supporting wheels keyed to said axle, a plurality of cutter-blades mounted on said wheels, 20 and a drum located between said wheels and provided with projections forming extensions of said cutter-blades.

2. A stalk-cutter including a frame, an axle journaled therein, a pair of blade-supporting wheels keyed to said axle, a plurality of cutter-blades mounted on said wheels, a hollow drum surrounding said axle and supported by said wheels, and a plurality of projections on said drum forming extensions of 25 said cutter-blades.

3. A stalk-cutter including a frame, an axle journaled therein, a pair of blade-support-

ing wheels keyed to said axle, each wheel having a groove in its inner face, a hollow drum surrounding said shaft and supported in said 35 grooves, a plurality of cutter-blades mounted on said wheels, and a plurality of projections on said drum forming extensions of said cutter-blades.

4. A stalk-cutter including a frame, an axle 40 journaled therein, a pair of blade-supporting wheels keyed to said axle, and a drum surrounding said axle between said wheels, said drum having a plurality of non-clogging 45 pockets.

5. A stalk-cutter including a frame, an axle journaled therein, a pair of blade-supporting wheels keyed to said axle, each wheel having a groove in its inner face, and a hollow drum surrounding said axle and having its 50 ends secured in said grooves, said drum having a plurality of non-clogging pockets.

6. A stalk-cutter including a frame, an axle journaled therein, a pair of blade-supporting wheels keyed to said axle, a plurality of 55 cutter-blades mounted on said wheels, each wheel having a groove in its inner face, and a hollow drum surrounding said axle and having its ends secured in said grooves, said drum having a plurality of pockets the side-walls of which merge into projections forming 60 extensions of said cutter-blades.

In testimony whereof I affix my signature.

GEORGE W. EDWARDS.
